UNITED STATES PATENT OFFICE.

OSCAR J. OLM, OF MINNEAPOLIS, MINNESOTA, ASSIGNOR OF ONE-HALF TO GUSTAV MONASCH, OF MINNEAPOLIS, MINNESOTA.

DISK-FEEDING DEVICE.

1,114,178.

Specification of Letters Patent. Patented Oct. 20, 1914.

Application filed February 5, 1912, Serial No. 675,674. Renewed August 22, 1913. Serial No. 786,182.

To all whom it may concern:

Be it known that I, OSCAR J. OLM, of Minneapolis, Hennepin county, Minnesota, have invented certain new and useful Im-
5 provements in Disk-Feeding Devices, of which the following is a specification.

My invention relates to improvements in machines for feeding and fastening disks of paper or other suitable material to en-
10 velops or sheets of paper, or other material, by means of eyelets, and the primary object of the invention is to provide means for rapidly and automatically feeding washer-shaped disks beneath a reciprocating plun-
15 ger and above an upsetting pin or horn, and simultaneously feeding an eyelet beneath the plunger and above the disk, the parts being so arranged that the downward movement of the plunger forces the eyelet through the disk and upsets its lower end, thereby fastening the disk to the desired sheet, and the upward movement of the plunger feeds another disk into position to be secured by an eyelet at the next down-
20 ward movement of the plunger.

A further object of my invention is to avoid the paper punching operation and make a material saving in the cost of putting the eyelets and disks on the paper.

30 In the accompanying drawings forming part of this specification, Figure 1 is a side elevation of the eyelet fastening machine with my invention applied thereto, showing the machine in its normal position, Fig. 2 is a similar view, showing the plunger depressed in the operation of fastening the eyelet and disk, Fig. 3 is a detail view, showing the receptacle in which the disks are placed and its position with respect to the eyelet feed, Fig. 4 is a detail view showing the connection between the plunger and the disk feeding mechanism, Fig. 5 is a front view of the attachment, Fig. 6 is a horizontal sectional view, showing the connection of the attachment to the machine head, Fig. 7 is a sectional view on the line $\alpha-\alpha$ of Fig. 4.

40 Referring to the drawings, 2 represents the head of the machine, supported on a suitable standard 3.

45 4 is the plunger, carrying the usual yield-

ing pin 5 and normally held in its raised position by springs 6. A lever 7 is pivoted at 8 on the head of the machine and has a roller bearing 9 on an arm 10 that is also 55 pivoted on the head 2 and adapted to bear on the plunger to depress the same when the lever 7 is drawn down by the treadle, not shown, that is attached to the bar 11.

12 is a hopper containing the eyelets fed 60 to the work through a way 13.

The mechanism so far described forms a part of the machine to which I make no claim in this application.

14 is a tube or barrel, secured by suitable 65 means to the head 2 and inclined slightly and provided with a plate 15 at its lower end. The disk used in this machine is usually of paper, having a central orifice and conforming to the shape of an ordinary 70 washer, the central opening being of suitable size to receive the eyelet 17, such as is usually employed for fastening the disk to an envelop for the purpose of securing the flap of the envelop by means of a string 75 wrapped around the eyelet under the disk. A reciprocating feed plate 18 is mounted on the underside of the plate 15 and has a depression 19 therein of sufficient depth to receive one of the disks, and is adapted to 80 push the disks, one at a time, from beneath the pile into a position, (shown plainly in Fig. 3), directly beneath an eyelet in the eyelet way 13 and in the path of the plunger. Beneath the plunger and the eyelet 85 way is an anvil 2' having a pin 3' mounted thereon in the path of the plunger. This pin operates in coöperation with its enlarged base to upset the lower end of the eyelet as the plunger descends.

90 Any suitable mechanism may be employed for reciprocating the feed plate 18 at predetermined intervals, but I prefer to provide an arm 20 attached to a plate 21 that is pivoted at 22 on a standard 23 which 95 projects upwardly from the disk receptacle. The plate 21 has a cam edge 23'. A collar 24 is mounted on the plunger and a bolt 25 passes through this collar and supports a barrel 26 that is adapted to receive 100 a plunger 27 on the upper end of a curved arm 28. A spring 29 is coiled on said plun-

ger within said barrel. The bolt 25 also carries an anti-friction roller 30 that is adapted to contact with the cam edge 23' when the plunger has been depressed to a certain point. The normal position of the feed plate is as shown in Fig. 3, with a disk in the path of the plunger, and the plunger descends to a point where it engages and holds the disk before the anti-friction roller contacts with the edge 22' to withdraw the feed plate. When this contact takes place, the feed plate is retracted, leaving the disk, and withdrawn to a point where the next disk will drop into the depression in the feed plate and be carried forward on the return stroke of the feed plate. The arm 28 is provided with a slot 31 to receive the pin 32 mounted in the plate 21, said slot allowing the arm 28 to slide toward said pin during the down stroke of the plunger, and on the up stroke the pin will contact with the end of the slot and swing the plate 21 inwardly to actuate the feed plate and project a disk into the path of the plunger. In case a disk should become jammed in the feed way, the spring 29 will yield and prevent breakage of the connections between the plunger and the plate.

In case the machine is operated at a high speed, a disk might be projected with sufficient force to fly out of the depression. I therefore prefer to provide retarding pins 33 which bear on the edge of the disk and hold it in place in the way. I also prefer to provide stop pins 34 in the underside of the eyelet way in the path of the disks to prevent the disks from being projected beyond the point where they will be engaged by the eyelet and the plunger.

In the operation of the machine, the eyelets and disks will be automatically fed into the path of the plunger, and the operator, instead of first punching a hole in the body of the envelop, as usually required, will insert the work between the plunger and the pin 3' and the descent of the plunger will punch a hole through the paper and secure the disk thereto with one operation.

I have shown the disk feeding mechanism operated through the movement of the plunger itself, but do not wish to confine myself to this method of operation, as the feed plate may be connected to some other moving part of the machine and still be within the scope of my invention.

I claim as my invention.

1. In a machine for fastening paper or other disks to suitable sheets, the combination, with a plunger and an eyelet feeding device for bringing an eyelet in alignment with the plunger, of an eyelet upsetting anvil in line therewith, a disk holder, a feed plate operating to protect and support a disk in the path of said plunger, means actuated by the downward movement of said plun-

ger to retract said feed plate and means actuated by the upward movement of said plunger for projecting a disk from said holder and supporting it beneath and in line with the plunger and anvil and the eyelet that is beneath the plunger, and means for reciprocating said plunger.

2. The combination, with a reciprocating plunger and means for feeding eyelets thereto, of a disk feeding device located near said plunger and including a disk receptacle, and means actuated by the up-stroke of said plunger for projecting a disk from said receptacle into the path of said plunger.

3. The combination, with a plunger and eyelet feeding means, of a disk receptacle, a feed plate having a depression therein adapted to receive a disk, said feed plate being normally projected to support a disk in the path of the plunger, and means connected with said feed plate and actuated by said plunger during the latter part of its down stroke to withdraw said feed plate when said disk has been engaged by said plunger, said means operating to project said feed plate on the upstroke of said plunger to feed a second disk into the path of said plunger and eyelet.

4. The combination, with a reciprocating plunger and means for feeding eyelets thereto, of a disk holder, a feed plate operating to project and support a disk in the path of said plunger, a pivoted cam plate connected with said feed plate, means carried by said plunger and adapted to engage said cam plate to retract said feed plate when said plunger on its down stroke has engaged the disk on said feed plate, and means connecting said cam plate with said plunger for advancing said feed plate and projecting another disk when said plunger has reached a predetermined point in its up stroke.

5. The combination, with a reciprocating plunger and means for operating the same and means for feeding eyelets into the path of the plunger, of a disk receptacle, a disk feeding device located near said plunger, a paper support beneath said plunger having an upwardly projecting pin, means carried by said plunger to retract the disk feeding device when the plunger is on its down stroke, and means connected with said plunger for projecting a disk when said plunger has reached a predetermined point in its upstroke.

6. The combination, with a reciprocating plunger and means for operating the same, of an eyelet feeding device having a way contiguous to said plunger in its normal position and in the path of the same, a disk feeding device having a feed plate near the discharge end of said way and also in the path of said plunger, a paper support in the path of said plunger and having a pin provided with an enlarged base coöoperating

with said plunger to punch the paper and insert an eyelet through a disk and through the hole in the paper and upset the eyelet with one operation, and means connected 5 with the plunger and actuated by the upward movement thereof for projecting a disk from said holder and supporting it beneath and in line with the plunger and an-

vil and the eyelet that is beneath the plunger.

In witness whereof, I have hereunto set my hand this 30th day of January 1912.

OSCAR J. OLM.
